DESIGN FOR A SMOKING PIPE

Adrien R. Mellor, Loma Linda, Calif.

Application March 30, 1945, Serial No. 118,788

Term of patent 14 years

(Cl. D85—8)

To all whom it may concern:

Be it known that I, Adrien R. Mellor, a citizen of the United States, residing at Loma Linda, in the county of San Bernardino and State of California, have invented a new, original, and ornamental Design for a Smoking Pipe, of which the following is a specification, reference being had to the accompanying drawing, forming part thereof.

In the drawing:

Figure 1 is a side elevational view of a smoking pipe showing my new design;

Figure 2 is a top plan view of a smoking pipe;

Figure 3 is a front elevational view thereof.

I claim:

The ornamental design for a smoking pipe, as shown.

ADRIEN R. MELLOR.
